UNITED STATES PATENT OFFICE.

CHARLES K. DUNLAP, OF HARTSVILLE, SOUTH CAROLINA, ASSIGNOR TO SONOCO PRODUCTS COMPANY, OF HARTSVILLE, SOUTH CAROLINA, A CORPORATION OF SOUTH CAROLINA.

CONE-TUBE-WINDING MANDREL.

Application filed March 22, 1923. Serial No. 626,988.

To all whom it may concern:

Be it known that I, CHARLES K. DUNLAP, a citizen of the United States, and residing at Hartsville, Darlington County, State of 5 South Carolina, have invented certain new and useful Improvements in Cone-Tube-Winding Mandrels, of which the following is a specification.

This invention relates to a device for 10 use in winding a sheet pattern of paper into the form of a cone including a plurality of layers and having open ends and which is adapted to receive and hold on its outer surface a comparatively large 15 body of thread, yarn or analogous material wound around it. Such cones are extensively used in the textile industry and are mounted on conical spindles in winding and unwinding; and it is essential to their suc- 20 cessful use that they shall accurately and closely fit the spindle to avoid looseness or lost motion and that the outer and inner surfaces shall be of as nearly uniform contour as possible, and shall be of such character 25 as to avoid slipping of the cone on the spindle and the slipping of the winding of yarn on the cone. The paper blank used is corrugated or otherwise treated to give it a rough surface. It is ordinarily sector shaped 30 in outline with two substantially straight edges meeting at an angle of about 150° but varying according to the taper of the cone so that one straight edge will be on the exterior and the other on the interior of the 35 finished cone and both will extend longitudinally of it. It is desirable that the longitudinal edges of the blank in the cone shall be in longitudinal planes passing through the axis of the cone, that they shall extend 40 substantially throughout the full length of the cone, and that they shall be thin so as to make the surfaces substantially regular. In machine made cones it is desirable from a commercial standpoint to sever the extreme 45 end portions of the cone from the balance on planes at right angles to the axis while the cone is still on the winding mandrel and one arrangement for doing this which has been found satisfactory in commercial use is 50 disclosed in the patent to W. F. Smith, 886,884, May 5, 1908. In this case, however, the inner straight edge of the blank does not extend quite to either end of the cone and it is at a slight angle to a longitudinal plane 55 through the axis.

My present invention consists in a cone winding mandrel having certain novel features of construction and arrangement of parts by which it is intended and adapted to wind sector shaped blanks having two straight edges of full length and to permit severing the ends of the cone while on the mandrel and to produce a finished cone in which the inner straight edge of the blank extends from the tip end substantially to the base end and which edge is substantially in a longitudinal plane through the axis of the cone. This last mentioned desirable arrangement of the inner edge is believed to be broadly new in machine made cones and the means for accomplishing it is of course equally new when broadly considered and therefore the invention is not limited to the specific means shown beyond what is set forth in the claims. The lightness of the 70 mandrel and the resulting saving in material and the simplicity of the shape and form of the cooperative parts making manufacture and assembly easy also constitute advantageous features of the present invention. 80

In the drawing showing one embodiment of the invention for purposes of illustration:

Fig. 1 is a longitudinal section through a mandrel embodying the invention showing the supports and operating gears diagrammatically and indicating in dotted lines a portion of the paper blank inserted in the slot in the mandrel to be wound; and 85

Fig. 2 is a cross section on the line 2—2 of Figure 1. 90

As will be seen by reference to Figure 1, the mandrel is composed of two parts, a solid cylindrical base portion 10 and a hollow tapered body portion 11 which terminates in the solid tip portion 12. The taper extends from the transverse plane 13 to the tip end and there is a cylindrical portion from 13 to 14 fitting in a peripheral groove 15 in the outer surface of the base portion, the depth of the groove being equal to the thickness of the material whereby the outer surface at the joint is cylindrical. A rotary supporting shaft 16 is secured in a central cylindrical opening 17 in the base portion 10 and is carried by any suitable supports such as 21 and 21' as is well known in the art. A longitudinal slot is formed in the body portion 11 entering the conical surface at a slight angle at the point 18 near the tip end of the mandrel and extending to the 105 110

point 19 near the larger end of the mandrel. The bottom surface 26 of the slot is parallel to the axis of the mandrel. A small rod 20 is rotatively mounted in the supporting pipe shaft 16 and extends longitudinally of the mandrel and at its inner end 22 is rotatively mounted in a cylindrical bearing socket 23 in the solid tip portion. A clamping member for engaging the edge of a sheet blank of paper inserted in this slot is mounted longitudinally on this rod 20 and cooperates with the edge of the slot for clamping the edge in place during winding. In the particular form of the invention shown 15 this clamping member 24 consists of a thin plate with one edge secured in a longitudinal groove 25 in the rod 20. The outer edge 27 of the clamping plate 24 has the same taper as the mandrel and is in the lines of 20 the cone constituting the mandrel's outer surface so that its outer thin edge may move in a rotary direction toward and against the sides of the slot so as to clamp the sheet of paper between it and the side of the slot at 25 the outer margin of the mandrel. It will be noted that since the surface 26 parallel to the axis of the mandrel and the body portion is hollow, the straight edge of a blank may enter the slot for its full length up to 30 the point 19 with its inner edge parallel all the way with the axis of the mandrel. Since the edge portion within the slot varies in width at substantially the same rate as the mandrel varies in diameter, when the winding is finished and this portion withdrawn 35 from the slot, its longitudinal edge when folded against the paper cone will be substantially in a plane longitudinally of the axis of the cone. The mandrel itself is rotated by any suitable means well known in 40 the art, the gear 28 being shown to illustrate this broadly. The rod 20 carrying the clamping plate 24 is of course rotated independently of the mandrel by suitable means 45 through gear 29. It will be noted that particular means for mounting and operating the mandrel and the clamping rod constitute no part of the present invention and that it is not necessary that the mandrel 50 shall be hollow in order that the edge of the paper may enter the slot or groove in parallel relation with the axis of the mandrel.

In operating the mandrel to wind a cone 55 a segmental blank of paper 30, indicated in part in dotted lines in Figure 1, is so moved that one of its straight edge portions will enter the slot preferably longitudinally until its curved end is substantially in contact 60 with the end wall 19 of the slot and the other end of said straight edge will extend towards the tip beyond the end 18 of the slot and this edge may be substantially parallel to the axis of the mandrel. A slight 65 rotation of rod 20 turning the clamp plate

24 in a rotary direction will cause it to cooperate with the edge of the slot to clamp the entering edge of the sheet blank thus securely holding it. The mandrel and the rod 20 are then rotated together for several 70 turns to wind the cone. The outer curved margin of the blank may be on such radii of curvature or so related to the straight edge in the slot, that it will extend longitudinally of the mandrel slightly beyond 75 the end 19 of the slot at each revolution or in each layer after the first and thus the end of the cone may be severed on the mandrel in a plane at right angles to its axis close to the end 19 of the slot. Since the 80 tip end of the blank extends beyond the end 18 of the slot it may, of course, be severed in the same way on a transverse plane beyond that end. The inner straight edge of the blank in the finished cone thus extends 85 entirely to the tip end and substantially to the other end and in a longitudinal plane passing through the axis of the cone.

Having thus described the invention what is claimed as new and desired to be secured 90 by Letters Patent is:

1. A conical mandrel for winding paper cones having a longitudinal slot therein entering said mandrel near its tip end at an angle to the surface of said mandrel and terminating near the larger end of the mandrel whereby the straight edge portion of a paper blank may be moved into it longitudinally from the end near the tip to the other end and relatively movable means in said slot 95 for detachably engaging and holding said edge during winding.

2. A conical mandrel for winding paper cones having a longitudinal slot therein entering said mandrel near its tip end at a 105 slight angle to the surface of said mandrel and terminating near the larger end of the mandrel whereby the straight edge portion of a paper blank may be moved into it longitudinally from the end near the tip to the other end and movable means in said slot 110 cooperating with one edge thereof for detachably engaging and holding said edge of said blank during winding.

3. A conical mandrel for winding paper 115 cones having a longitudinal slot therein entering said mandrel near its tip end at a slight angle to the surface of said mandrel and terminating near the larger end of the mandrel whereby the straight edge portion 120 of a paper blank may be moved into it longitudinally from the end near the tip to the other end, a movable clamping member in said slot having a straight narrow outer edge on substantially the same circular 125 transverse lines as the adjacent portions of the mandrel extending from approximately the end of the slot near the base of the mandrel to a point a material distance from the end near the tip and means for so operating 130

said member as to cause its outer edge to move into or out of lateral contact with an edge of said slot.

4. A conical mandrel for winding paper cones having a longitudinal slot therein entering said mandrel near its tip end at a slight angle to the surface of said mandrel and terminating near the larger end of the mandrel whereby the straight edge portion 10 of a paper blank may be moved into it longitudinally from the end near the tip to the other end, a movable clamping member in said slot having a straight narrow outer edge on substantially the same circular 15 transverse lines as the adjacent portions of the mandrel extending from approximately the end of the slot near the base of the mandrel to a point a material distance from the end near the tip and rotary means entering 20 the base of said mandrel centrally for so operating said member so as to cause its outer edge to move into or out of lateral contact with an edge of said slot.

5. A conical mandrel for winding paper cones having a longitudinal slot therein entering said mandrel near its tip end at a slight angle to the surface of said mandrel and terminating near the larger end, a rod 25 rotatively mounted centrally of said mandrel and projecting from its base for operation, and a clamping member mounted on said rod having an outer straight edge in but of less width than said slot from its end next to the base to a point near the other 30 end, the said outer edge having the same longitudinal taper as the adjacent sides of the slot whereby it will cooperate with one side of said slot in clamping the edge of a paper blank.

6. A conical mandrel for winding paper cones having a longitudinal slot therein entering said mandrel near its tip end at a slight angle to the surface of said mandrel and terminating near the larger end, a rod 40 rotatively mounted centrally of said mandrel and projecting from its base for operation, a clamping member in the form of a thin flat sheet rigidly connected at its inner edge longitudinally to said rod and extending therefrom radially with its outer

edge between the sides of said slot at the outer margin of the mandrel from its base end of said slot to a point near its other end.

7. A conical mandrel for winding paper cones having a hollow body portion, a solid tip portion, a substantially solid base portion and a longitudinal slot entering its surface in a plane parallel to its axis near its tip end and terminating at a point near its 50 base end, a supporting tube centrally arranged in the base portion and projecting therefrom, a rotary rod in said tube projecting beyond its ends its inner end being in a bearing socket in the tip portion, a clamping 55 member in the form of a thin flat sheet with its inner edge secured in a longitudinal slot in said rod extending therefrom radially with its outer edge between the sides of said slot at the outer margin of the mandrel from substantially the end of the slot 60 at the base of the mandrel to a point near the other end of the slot.

8. A conical mandrel for winding paper cones having a longitudinal slot therein between but spaced from its ends adapted to receive therein the straight edge portion of a paper blank the width of said edge portion in the slot varying longitudinally in correspondence with the varying radii of the 70 adjacent portions of the mandrel and relatively movable means in said slot cooperating with one side wall thereof for detachably engaging and holding said edge portion during winding.

9. A conical mandrel for winding paper cones having a longitudinal slot therein entering said mandrel near its tip end in a plane parallel to its axis and terminating near the larger end of the mandrel whereby 80 the edge portion of a paper blank may be inserted with its edge substantially parallel to the axis of the mandrel and relatively movable means in said slot for detachably engaging and holding said edge during 85 winding.

In testimony whereof I hereunto affix my signature.

CHARLES K. DUNLAP.
